(57) **CLAIM**

We claim the ornamental design for a firearm sound suppressor, as shown and described.

DESCRIPTION

FIG. 1 is an isometric view of an embodiment of our design for a firearm sound suppressor;
FIG. 2 is a right side view of the design for the firearm sound suppressor shown in FIG. 1;
FIG. 3 is a left side view of the design for the firearm sound suppressor shown in FIG. 1;
FIG. 4 is a front view of the design for the firearm sound suppressor shown in FIG. 1; and,
FIG. 5 is a rear view of the design for the firearm sound suppressor shown in FIG. 1.
The broken lines are for illustrative purposes only and form no part of the claimed design.
